UNITED STATES PATENT OFFICE.

WILLIAM H. CRICHTON-CLARKE, OF NEW YORK, N. Y., ASSIGNOR TO GILLETTE SAFETY RAZOR COMPANY, OF BOSTON, MASSACHUSETTS, A CORPORATION OF MASSACHUSETTS.

SAFETY-RAZOR.

1,071,711.

Specification of Letters Patent.

Patented Sept. 2, 1913.

Application filed July 20, 1907. Serial No. 384,797.

To all whom it may concern:

Be it known that I, WILLIAM H. CRICHTON-CLARKE, a citizen of the United States, residing in the city, county, and State of New York, have invented certain new and useful Improvements in Safety-Razors, of which the following is a full, clear, and exact specification.

This invention relates to safety razors.

10 The objects of the invention are to improve and simplify the construction of such devices, particularly by reducing the number of parts of which they are made.

With the foregoing and other objects in view, which will appear as the description proceeds, the invention resides in the combination and arrangement of parts and in the details of construction hereinafter described and claimed, it being understood 20 that changes in the precise embodiment of invention herein disclosed can be made within the scope of the following claims without departing from the spirit of the invention.

25 In the accompanying drawing forming part of this specification, Figure 1 is a vertical section, partly in elevation through a razor constructed in accordance with the invention. Fig. 2 is a vertical section showing the cap and guard separated from each other.

30 Fig. 3 is a plan view of the improved razor. Fig. 4 is a sectional view at right angles to Fig. 2. Fig. 5 is a side elevation of the cap, blade, guard and handle 35 in separated relation; and Fig. 6 is a plan view showing a portion of the blade.

Like reference numerals indicate corresponding parts in the different figures of the drawing.

40 The numeral 1 indicates the cap or back- ing; 2 the blade; 3 the guard, and 4 the handle. The handle 4 is swiveled on to the guard 3 in any suitable manner. One convenient method of swiveling the handle on 45 to the guard for permitting rotary movement of the handle while preventing movement of the guard axially consists in ex- tending the upper end of the handle above the guard 3 as shown at 5, and forming it

50 with an annular enlargement to produce a shoulder 6 which rests against the upper surface of the guard 3. Below the guard 3, a ring or washer 7 is secured to the handle 4 by means such as bolts 8. The shoulder 6

and ring 7 provide a simple form of swivel joint between the guard 3 and handle 4. The upward extension 5 of the handle 4 is formed to engage the cap, it is preferably screw threaded as indicated at 9 and is adapted to engage a screw threaded opening 60 10 in the cap 1 for the purpose of adjustably drawing the cap 1 and guard 3 together so as to clamp the blade 2 between them. The cap and the guard thus form a pair of blade clamping plates. The cap and guard are 65 preferably so shaped as to flex or bend the blade 2 in the usual manner and the cap 1 is provided with positioning pins 12 and adapted to extend through openings 13 in the blade 2 and through openings 14 in the 70 guard 3. The teeth 15 preferably are formed on the opposite edges of the guard 3 in the usual manner. The blade 2 is formed with an opening 16 for the passage of the extension 5 of the handle 4. By 75 swiveling the handle 4 on to the guard 3 and by providing said handle with an upward extension adapted to engage the cap 1 the construction of the razor is simplified and improved and the number of main 80 parts are reduced to three, viz: the cap, the guard and the swiveled handle.

What is claimed is:

1. A razor comprising a cap having a threaded opening, a guard, and a handle 85 rotatably swiveled on the guard and having an enlarged threaded extension at its upper end projecting above the guard and adapted to engage the threaded opening of the cap, and means for preventing axial movement 90 of the handle relative to the guard.

2. A razor comprising a perforated guard, a handle passing therethrough, and a swivel connection between the two, a cap having a threaded aperture, and a threaded enlargement 95 on the end of the handle constructed and adapted to enter the cap aperture, and means coöperative with such enlargement for holding the guard from movement axially of the handle.

100 In testimony whereof, I have hereunto set my hand in the presence of two subscribing witnesses:

WILLIAM H. CRICHTON-CLARKE.

Witnesses:

CHARLES A. SCHEUBER,
HERMAN P. SCHWARTZ.
